Filed Mar. 14, 1961, Ser. No. 64,279

Term of patent 14 years

(Cl. D90—20)

FIG. 1

FIG. 2

FIG. 3

FIG. 4

FIG. 1 is a fragmentary perspective view of a tire showing my new design;

FIG. 2 is an enlarged fragmentary plan view of a portion of the tire's side and road engageable surfaces;

FIG. 3 is a fragmentary sectional view taken on line 3—3 of FIG. 2; and

FIG. 4 is a reduced side elevation of the tire design.

It being understood that the full-line portions are repeated throughout the circumference of the tire shown by means of broken lines.

I claim:

The ornamental design for a tire, as shown and described.
